UNITED STATES PATENT OFFICE.

WILLY JENNY, OF HOUSTON, TEXAS, ASSIGNOR TO ROXANA PETROLEUM CORPORATION, A CORPORATION OF VIRGINIA.

CALCULATING MACHINE.

Application filed November 14, 1925. Serial No. 68,945.

This invention relates to improvements in calculating machines.

In certain arithmetical calculations, it is necessary to utilize a formula comprising a series of numbers having a plus and minus digit and zero values. For instance, the numeral 3 is required to be multiplied by a series of multipliers, such, for instance, as plus one, minus one, zero, and so forth. The formula is standard and the sequence of numbers constituting the multipliers remains constant in the same series.

The calculations may also comprise the multiplication of one number simultaneously by a series of numbers constituting separate formulae.

An object of the present invention, therefore, is to provide a calculating device whereby through adding and subtracting operations, a series of products may be obtained and totaled, using a selected number for the multiplicand and the formula series of numbers as the multipliers.

With the foregoing, as well as other detailed advantages in view, the construction hereinafter disclosed has been designed, reference being made to the accompanying drawing in which,

Fig. 1 is a plan view of the mechanism; and,

Fig. 2 is an end elevation.

In the embodiment of the invention illustrated in the drawing, the device is shown as including a pair of intermeshing gear wheels 1 and 2, said wheels being fixed to the shafts 3 and 4. Each of the gear wheels 1 and 2 has a hub 5 and 6 respectively, said hubs having rigidly attached thereto one member of a coupling device 7 and 8 respectively. One of the wheels 1 or 2, and in the embodiment shown, the wheel 2, is operatively connected with a key 9 having a pawl 10 at its inner end and a finger piece 11 at its outer end, said key being pivoted on a shaft 12. The arrangement of the pawl is such that upon the depression of the key, the wheel 2 will be rotated in the direction of the arrow, Fig. 2, one tooth distance for each depression of the key. Obviously, the operation of the gear wheel 2 imparts a reverse rotation to the gear wheel 1.

The result of the separate calculations is accumulated in separate series of accumulating wheels 13, mounted in housings disposed longitudinally of the shafts 3 and

4 and preferably placed between the shafts. Insomuch as the accumulating wheels constitute recognized accumulating mechanism, the details of the accumulating group will be understood without specific description. 60 Each group of accumulators is actuated by a wheel 14 disposed at one end of the group, said wheel 14 being operatively connected with the shafts 3 and 4 by mechanism about to be described.

As each of the group of accumulators is of duplicate construction, and as the operative connections between the accumulators and the shafts 3 and 4 are similar, it will be understood that the explanation of one 70 group will apply to the series of accumulators and their connections that may be incorporated in the machine, it being understood that the number of accumulators may be any predetermined or desired number.

The connections between the shafts 3 and 4 with the actuating wheel 14 of the accumulator groups comprise wheels 15 and 16 respectively loosely mounted upon the shafts 3 and 4. Each of the wheels 15 and 16 is 90 formed with a recess 17 adapted to engage with a lug 18 of the coupling devices 7 and 8. The wheels 15 and 16, as well as the accumulator actuators 14, are formed with smooth peripheries so that by frictional contact, the wheel 14 may be moved alternatively in one or the other direction, according to its relationship with the wheels 15 and 16. In order to alternately and selectively couple the wheels 15 and 16 for rotation by the 90 shafts 3 and 4 respectively, the said wheels 15 and 16 are connected with opposite ends of a lever 19 pivoted at 20 by links 21 and 22.

By reference to Fig. 1 of the drawing, it will be noted that the upper group of connections illustrate the wheel 15 as operatively connected with the shaft 3. The lower group of connections illustrate the couplings in neutral position where both the wheels 15 and 16 idle on the shafts 3 and 4.

The selective devices for determining the ultimate direction of rotation of the actuator member 14 of the accumulator group comprise plates having predetermined configuration of cams on their marginal edges. The cams for each group, while different in formation, operate upon the same principle and may be conveniently described together.

Each of the cam plates 23 is revolvably mounted on a stud shaft 24, said shaft 24 110

being disposed at right angles to the axis of the shafts 1 and 2. The cams are operatively connected with one end of the lever 19 by an extension 25 of the link 22. The 5 free end of the link 22 carries a cam roller 26 that operates against the cam face of the plate 23. The cam face of the plate 23 is arranged to actuate the lever 19 so that the lever will assume three distinct positions, 10 the one as illustrated in the upper part of Fig. 1, in which the wheel 15 is operatively connected with the shaft 3, the other being the intermediate position illustrated in the lower group of accumulator connections in 15 Fig. 1, and the third position in which the wheel 16 is operatively connected with the shaft 4. Thus, the cams determine a plus or minus operation of the accumulator group and also a neutral position in which the key 20 may be actuated without influencing the accumulators. The lever 19 is actuated by an expansion spring 27, the normal tendency of which is to depress the arm of the lever remote from the cam actuator, it being obvious 25 that when the roller 26 rides upon a high point of the cam, the arm of the lever 19 adjacent to the cam will be depressed, thereby coupling the wheel 16 with the shaft 4. When the roller 26 rides upon an intermediate point of the cam, the coupling device will be in the intermediate position shown at the lower part of Fig. 1, and likewise when the roller 26 rides against a low part of the cam, the wheel 15 will be coupled 30 with the shaft 3.

Each of the plates is formed with double contact surfaces so that the complementary value on one face of the cam is provided on the other face of the cam. That is to say, 40 for a corresponding high point on the upper part of the cam, there is a complementary low part on the under part of the cam. This arrangement is to provide for adjusting the result of a multiplication to correspond with 45 the plus or minus values of the multiplier and the multiplicand. The cam plate 23 is therefore carried on a support 27 that imparts an axial movement to the cam. It will be noted in Fig. 2 that the periphery of the 50 cam disk is formed with an offset face so that for each high point there is a complementary low point located in the lower horizontal plane.

When it is desired to give a reverse value 55 to the product, the support 24 is moved upwardly to bring the cam wheel 26 into contact with the complementary face of the cam disk. The longitudinal movement of the support 27 may be imparted by any suitable 60 mechanism, for instance, by an eccentric device 28 operable by means of a key extending exteriorly of the frame of the machine.

The rotation of the cam disks 23 is accomplished in unison by means of pawl and 65 ratchet devices 29 pivoted at 30 to a bar 31,

said bar being operable by a handle 32, preferably extending exteriorly of the frame of the machine and being manually movable outwardly to rotate the cam disks on their supports one tooth distance for each adjusting operation of the disks. It is understood 70 that the ratchet teeth of the pawl and ratchet device are spaced so as to rotate the cam disks predetermined intervals upon each operation of the handle 32 so as to bring in rotation the desired cam surfaces into contact 75 with the cam wheel 26.

From the foregoing, it will be understood that the operation of the device is as follows:

For example, selecting the numbers plus 80 one and minus one as the multiplicand and multiplier respectively, the multiplier will be represented in accordance with its value by the formation of the cam. The operating key will be depressed the value of one digit. 85 The product of the plus and minus values will be a minus product. Therefore, the wheel 15 will be operatively connected with the shaft 3, thereby imparting a reverse direction of rotation to the actuator of the 90 accumulator 14 representing a minus product of one.

Similarly utilizing plus one as a multiplicand and plus one as a multiplier, the multiplier plus value will be represented by the high point of the cam disk actuating the coupling device, so that the shaft 4 is operatively connected with the wheel 16. Therefore, upon the depression of the key, a plus product will be set up in the actuator 14 of 100 the accumulator group. If a negative value is multiplied by a negative value, the cam will be adjusted to bring the complementary face thereof into contact with the cam wheel, reversing the normal position of the coupling devices and representing a plus product. In any multiplication of zero, either 105 in the multiplier or in the multiplicand, the coupling devices assume a neutral position and there will be no accumulation in the 110 accumulator.

It is thus seen that the device provides means for selectively representing series of plus, minus and zero values of the multiplier in predetermined sequence corresponding to the formation of the cam faces. 115

I am aware that the invention may be modified in many particulars and that the principles thereof may be embodied in widely varying structures.

I do not limit myself, therefore, to the construction shown and described; but what I claim and desire to secure by Letters Patent is:

1. In a calculating machine, a pair of 125 parallel rotating shafts, gearing for rotating one of said shafts by the other, manual means for rotating one of said shafts, a wheel loose on each of said shafts, an element on each of said shafts for rotating said wheels 130

- respectively, a lever for shifting said wheels laterally on said shaft to and from engagement with said elements respectively, an actuating wheel in position to be engaged and 5 rotated by any one of said first two wheels that is in engagement with the corresponding rotating element therefor, and accumulating pinions controlled by said actuating wheel.
- 10 2. In a calculating machine, a pair of parallel rotating shafts, gearing for rotating one of said shafts by the other, manual means for imparting successive step-by-step rotary movements to one of said shafts, a 15 driving element attached to each of said shafts, a wheel on each of said shafts shiftable into and out of engagement with the corresponding driving element, an actuating pinion in position to be engaged by any 20 one of said first two wheels that is in engagement with the corresponding driving element therefor and that is out of engagement with the other one of said wheels, means for shifting said first two wheels to 25 and from engagement with said driving elements, and accumulating pinions controlled by said actuating wheel.
3. In a calculating machine, a pair of parallel rotary shafts, gearing for rotating one of said shafts by the other, manual means for rotating that shaft which rotates the other shaft by said gearing, a driving element on each of said shafts, a wheel loose 30 on each of said shafts, connections for mov-
- ing said two wheels simultaneously in opposite directions on said shafts to engage one of said wheels with the corresponding driving element and to disengage the other one of said wheels from its corresponding driving element and vice versa, means for 35 operating said connections as aforesaid, an actuating wheel in position to be rotated by that one of said two wheels which is in engagement with the corresponding driving element therefor, and accumulating 40 pinions controlled by said actuating wheel.
4. In a calculating machine a pair of parallel rotary shafts, gearing for rotating one of said shafts by the other, manual means for rotating that shaft which rotates the other, a number of driving elements attached to each of said shafts for rotation thereby, a corresponding number of wheels loosely 45 mounted on each shaft, connections for moving said wheels on said shafts to and from engagement with the corresponding driving elements, mechanism for selectively moving said wheels on said shafts to engagement with the corresponding driving elements or out of engagement with the corresponding 50 driving elements as desired, a number of series of accumulating pinions, and an actuating wheel for each series of accumulating pinions in position to be engaged and rotated by an adjacent one of said first wheels that is in engagement with said actuating element.

WILLY JENNY.
